Primary Examiner — Vy N Koenig*Assistant Examiner* — Qiawen W Wiechert(74) *Attorney, Agent, or Firm* — Ying-Ting Chen; Law Office of Michael Chen(57) **CLAIM**

The ornamental design for a cabinet, as shown and described.

DESCRIPTION

FIG. 1 is a perspective view of the cabinet showing my new design;

FIG. 2 is a perspective view thereof from another angle;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is an enlarged view of the encircled portion labeled

9 in FIG. 1; and,

FIG. 10 is an enlarged view of the encircled portion labeled

10 in FIG. 1.

The evenly dashed broken lines in the drawings illustrate portions of the cabinet that form no part of the claimed design.

The long dash-short dash broken lines illustrate boundaries of the enlarged views and form no part of the claimed design.

1 Claim, 10 Drawing Sheets(56)
